UNITED STATES PATENT OFFICE.

ANDREW F. SPROUL, OF OAKLAND, CALIFORNIA.

SECONDARY FUSE-BLOCK.

1,262,861.

Specification of Letters Patent. Patented Apr. 16, 1918.

Application filed January 29, 1917. Serial No. 145,194.

To all whom it may concern:

Be it known that I, ANDREW F. SPROUL, a citizen of the United States, residing at Oakland, in the county of Alameda and State of California, have invented certain new and useful Improvements in Secondary Fuse-Blocks, of which the following is a specification.

This invention relates to improvements in secondary fuse blocks for holding a standard link fuse.

The object of the invention is to provide a simply and cheaply constructed device of this character which is positive in action and may be easily repaired.

This invention consists in matters hereinafter set forth and more particularly pointed out in the appended claims.

20 In the accompanying drawings:—

Figure 1 represents a side elevation of a fuse block constructed in accordance with this invention,

Fig. 2 represents a top plan view thereof,

25 Fig. 3 is a longitudinal central section taken on the line 3—3 of Fig. 2,

Fig. 4 is a transverse vertical section taken on the line 4—4 of Fig. 3.

In the embodiment illustrated this improved device comprises two tubular contacts 1 and 2 preferably composed of brass castings, the outer ends of the bores 3 being of smaller diameter than those of the inner ends and are designed to receive the conducting wires W, which latter are held in engagement with said castings by set screws 4.

40 The enlarged inner ends of the bores of these castings have shoulders 5 formed at their junction with the reduced outer ends thereof, and mounted in these enlarged bores is a core or connector 6 of insulating material. This core 6 is preferably composed of maple wood and the ends thereof are driven into the enlarged bore ends of the castings

45 1 and 2 to form a driven fit, shoulders 7 being formed on said core and which abut against the opposed inner ends of the castings 1 and 2, and operate to hold the castings in spaced relation.

50 The ends of the core 6 have threaded apertures 8 extending transversely therethrough and are designed to receive screws 9 which pass through openings 10 in the inner ends of the castings 1 and 2, and through the apertures 8 in said core thereby securely connecting the castings to the core. Wash-

ers as 11 are mounted on these screws between the heads thereof and the opposed outer faces of the castings, and are adapted for clamping the ends of a fuse link L 60 which electrically connects the two castings, and is composed of any suitable fusible metal which will melt and disconnect the castings should it be subject to an excessive temperature.

65 This improved fuse block is designed for use in connection with two transformers (not shown) of an electric lighting circuit, said transformers designed to operate in connection with each other for supplying the electric current for the lights. Should one of the transformers become defective it may be removed and taken to a testing room for repairs and the wires which were connected with said transformers will be inserted in the small bores of the fuse block which constitutes this invention and secured therein by the set screws 4.

70 From the above description it will be obvious that this device is simple in construction and efficient in operation, and by using the link fuse L in connection therewith will fully protect a transformer.

75 From the foregoing description, taken in connection with the accompanying drawing, 85 the advantages of the construction and of the method of operation will be readily apparent to those skilled in the art to which the invention appertains and while I have 90 described the principle of operation of the invention together with the device which I now consider to be the best embodiment thereof, I desire to have it understood that the device shown is merely illustrative and 95 that such changes may be made as are within the scope of the claimed invention.

I claim as my invention:

1. In a device of the class described, a 100 pair of tubular castings of conductive material, a connecting and spacing core of insulating material having its ends disposed in the opposed ends of said castings whereby 105 said castings are spaced apart, screws extending transversely through one wall of the castings and through said spacing member thereby connecting said castings and member, and wire securing screws extending transversely through one wall of the other end of the castings.

110 2. In a device of the class described, a pair of tubular castings, the bore of each

- being larger at one end than at the other; a connecting and spacing core of insulating material having its ends disposed in the larger bore ends of said castings, screws extending transversely through one wall of the larger bore ends of the castings and through said spacing member, and wire securing screws extending transversely through one wall of small bore ends of said castings.
3. In a device of the class described, a pair of tubular castings of conductive material, the bore of each being larger at one end than at the other with a shoulder at the meeting ends of said larger and smaller bore portions, a connecting and spacing core of insulating material having its ends disposed in the larger bore ends of said castings and of a length greater than the combined length of the larger bore ends of the two castings whereby said castings are spaced apart, screws extending transversely through one wall of the larger bore ends of the castings and through said spacing member thereby connecting said castings and member, and wire securing screws extending transversely through one wall of the small bore ends of said castings.
4. A fuse block of the class described comprising two tubular brass castings, the bore of each of which is smaller at one end than at the other, a shoulder formed at the meeting ends of the larger and smaller bore portions of each casting, the screws extending through one wall of the larger bore end of each casting and having a washer thereon outside of said casting, a connector for said castings composed of insulating material having the ends thereof disposed in the larger bore ends of the castings and provided with transversely extending passages communicating with the apertures in said castings when in operative position to receive said screws, said connector having longitudinally spaced shoulders abutting the outer ends of the castings when in operative position for limiting the insertion of said connector in said castings, and set screws for connecting the wires of the electric circuit with the smaller bore ends of said castings.

In testimony whereof I affix my signature in presence of two witnesses.

ANDREW F. SPROUL.
